[75] Inventor: Anthony C. Donato, Wellesley, Mass.

Primary Examiner—Susan J. Lucas
Attorney, Agent, or Firm—Middleton Reutlinger; Jeffrey A.
Haeberlin

[73] Assignee: Genlyte Thomas Group LLC,
Louisville, Ky.

[57] CLAIM

[**] Term: 14 Years

I claim the ornamental design for a modular construction for
track lighting fixture, as shown and described.

[21] Appl. No.: 29/122,628

DESCRIPTION

[22] Filed: May 1, 2000

FIG. 1 is a front isometric view of the modular construction
for track lighting fixture of the invention;

[51] LOC (7) Cl. 26-05

FIG. 2 is a rear isometric view of the modular construction
for track lighting fixture of FIG. 1; and,

[52] U.S. Cl. D26/63; D26/118

FIG. 3 is a bottom plan view of the modular construction for
track lighting fixture of FIG. 1.

[58] Field of Search D26/60-66, 118;

The broken lines shown in FIGS. 1-3 are for illustrative
purposes only and form no part of the claimed design.
